[57] ABSTRACT

An improved electromagnetic switching device having switch means mounted within a housing. The housing has front and rear sections, and first and second side

sections interposed between the front and rear sections. The front and rear sections and the first and second side sections each have windows extending therethrough. A movable magnet is mounted in the housing and positioned for reciprocal movement between an energized and a deenergized position. An operating coil for energizing the device is positioned in the housing so that one end of the coil is retained within the window in the front section of the housing and the other end of the coil is retained within the window in the rear section of the housing. The coil has an opening therethrough for receiving a stationary magnet which is in juxtaposition with the movable magnet. One end of the stationary magnet is positioned within the window in the first side section of the housing, and the other end of the stationary magnet is positioned within the window in the second side section of the housing to prevent removal of the coil through the window in the front section. Means is provided for actuating the switch means in response to movement of the movable magnet. Means are also provided for holding the stationary magnet within the respective windows in the first and second side sections of the housing, whereby upon release of the holding means, the stationary magnet is removable from the opening in the coil so as to enable the coil to be removable from the housing through the window in the housing's front section.

ELECTROMAGNETIC SWITCHING ASSEMBLY

BACKGROUND OF THE INVENTION

1. Field of the Invention

This invention relates to an electromagnetic switching device, and more particularly to an electromagnetic switching device which can have its operating coil removed without requiring the disassembly of the device's housing.

2. Description of the Prior Art

Electromagnetic switching devices, and more particularly an industrial control relay described in copending U.S. application Ser. No. 383,685, filed July 30, 1973, inventors Phillip G. Hughes and Dorsey Hardman, entitled Industrial Control Relay, and assigned to the assignee as the assignee of the present invention, is provided with switch means mounted within a housing. Also mounted within the housing is a stationary magnet positioned within an opening in an operating coil and a movable magnet positioned for reciprocal movement between an energized and a deenergized position. Means is provided for actuating the switch means in response to movement of the movable magnet. The housing is comprised of a plurality of molded sections which are fastened together in a box-like construction.

Quite often, when the operating coil fails, or when there is a design or system change, replacement of the operating coil becomes necessary. However, such replacement of the operating coil requires unfastening and disassembly of the housing sections and many of the relay components. Therefore, upon replacement of the operating coil, many components of the relay would have to be reassembled and the housing sections would have to be refastened together again. This is not only time consuming, but when the operating coil is replaced under field conditions, various components of the relay can be misplaced so as to prevent it from being placed back into operation.

OBJECTS OF THE INVENTION

It is therefore an object of this invention to provide an improved electromagnetic switching device which is capable of having its operating coil replaced without requiring disassembly of the device's housing and various other components.

It is another object of this invention to provide for quick and easy replacement of the operating coil of the relay without running the risk of having various components of the relay misplaced in the interim.

Other objects of the invention will be pointed in and understood from the following.

SUMMARY OF THE INVENTION

In accordance with a broad aspect of the invention there is provided an electromagnetic switching device having switch means mounted within a housing. The housing has front and rear sections, and first and second side sections interposed between the front and rear sections. The front and rear sections and the first and second side sections each have windows extending therethrough. A movable magnet is mounted in the housing for reciprocal movement between an energized and a deenergized position. An operating coil for energizing the device is positioned in the housing. The coil has an opening therethrough, and one end of the coil is retained within the window of the front section of the

housing. A stationary magnet is positioned within the opening in the coil and in juxtaposition with the movable magnet. Means for actuating the switch means in response to movement of the movable magnet is provided. Also provided is means for holding one end of the stationary magnet within the window in the first side section of the housing to prevent removal of the coil through the window in the front section, whereby upon release of the holding means, the stationary magnet is removed from the opening in the coil to enable the coil to be removed from the housing through the window in the front section. The holding means is comprised of a spring member positioned within a pocket in the housing and pressing against a bottom portion and a substantially vertical side wall portion bounding a channel formed within the top surface of the stationary magnet. Also provided is a flat spring which bears against the top of the operating coil so as to prevent any unnecessary movement of the coil during operation of the relay.

BRIEF DESCRIPTION OF THE DRAWINGS

FIG. 1 is a perspective view of the assembled electromagnetic device;

FIG. 2 is an exploded perspective view of elements of the device shown in FIG. 1 showing the removal of the operating coil through the window in the front section of the housing;

FIG. 3 is a side elevation view of the lower half of the relay;

FIG. 4 is a cross sectional view of the lower half of the relay taken along lines 4-4 in FIG. 3; and

FIG. 5 is a cross sectional view of the lower half of the relay taken along lines 5-5 in FIG. 4.

DESCRIPTION OF THE PREFERRED EMBODIMENT

The invention will now be explained with reference to FIGS. 1-5. As shown in FIG. 1, the housing for a relay 10 is comprised of a metal base plate 12, a pair of molded plastic lower half sections 14a and 14b, a molded plastic upper housing section 16 and a molded plastic housing cover 18. Lower molded half sections 14a and 14b are fastened to base plate 12 using respective threaded fasteners 19a and 19b. Upper housing section 16 is fastened to lower molded half sections 14a and 14b using standard fastening techniques, such as a threaded fastener 20. Similarly, housing cover 18 is fastened to upper housing section 16 using threaded fasteners 21a and 21b.

As more specifically shown in FIGS. 2 and 4, relay 10 is further comprised of a U-shaped movable magnet 22 mounted within the housing for reciprocal movement between an energized and a deenergized position. An operating coil 24, having an opening 26 therethrough and first and second current carrying terminals 28a and 28b extending therefrom, is suitably mounted within the housing. A one piece rigid member 30 has portions 32a and 32b fixed to respective pole faces 34a and 34b of magnet 22. Member 30 has actuating portions 36a and 36b extending upwardly from the pole faces of movable magnet 22. Switch means, in the form of a plurality of switch modules, is provided, although in FIG. 2 only a single switch module 38 is shown. Means for actuating the switch means is provided by a one piece yoke member 40 having raised portions 42 extending from a top surface thereof to form pockets, wherein

each pocket receives one end 44 of a plunger 46 that extends through the bottom of an enclosure 48 for switch module 38. The other end 50 of plunger 46 engages spring loaded means mounted within housing cover 18. A shaft 52, shown in FIG. 1, extends from the top surface of yoke 40 and through the top surface of housing cover 18. A stationary magnet 54 is positioned within opening 26 of coil 24, and is placed juxtaposition with the pole faces of movable magnet 22. A more detailed description of the relay's components such as movable magnet 22, rigid member 30, operating coil 24, switch module 38, yoke 40, stationary magnet 54, etc., their method of assembly and operation is found in copending U.S. application Ser. No. 383,685, filed July 30, 1973, inventors Philip G. Hughes and Dorsey Hardman, entitled "Industrial Control Relay," and assigned to the same assignee as the assignee of the present invention. Only those details of the relay components and housing necessary for the understanding of this invention will now be further explained.

A front section 56 of the relay housing has a window 58 therein which is dimensioned to allow coil 24 to pass therethrough. A rear section 60 of the housing also has a window 62 therein which is of the same approximate dimension as the dimension of window 58. A one piece bowed spring member 64, having opposite ends 66a and 66b located within respective pockets 68a and 68b formed by the molded interior of the housing, is shown in FIG. 5 to bear against the top surface of coil 24 so that those portions of the bottom surface of the coil which are adjacent opposite ends thereof bear against respective lower ledges 70a and 70b of respective windows 58 and 62. Bowed spring 64 applies sufficient force to coil 24 to prevent the coil from moving unnecessarily during operation of the relay.

As shown in FIG. 4, a first side section 72 of the housing has a window 74 therein dimensioned to allow stationary magnet 54 to pass therethrough. Similarly, a second side section 76 of the housing has a window 78 therein which also is dimensioned to allow stationary magnet 54 to pass therethrough. As shown in FIG. 4, when the relay is assembled, stationary magnet 54 is positioned within opening 26 in coil 24, and those portions of the bottom surface of magnet 54 adjacent its respective opposite ends respectively rest on a ledge 80 of window 74 and a ledge 82 of window 78. A first channel 84 is formed within a top surface and adjacent an end 85 of stationary magnet 54 that is positioned within window 74 of first side section 72 of the housing. Similarly a second channel 86 is formed within the top surface and adjacent the other end 87 of stationary magnet 54 that is positioned within window 78 of second side section 76 of the housing. Channel 84 is bounded by a bottom portion 88, a substantially vertical side wall portion 90 extending upwardly from one edge of bottom portion 88, and an upwardly extending sloping side wall portion 92 extending upwardly from the opposite edge of bottom portion 88 and toward the second side section of the housing. Vertical side wall portion 90 is positioned closer to window 74 in first side section 72 of the housing than is upwardly extending sloping side wall portion 92. Second channel 86 is likewise bounded by a bottom portion 94, a substantially vertical side wall portion 96 extending upwardly from one edge of bottom portion 94, and a sloping side wall portion 98 extending upwardly from the opposite edge of bottom portion 94 and toward first side section

72. Vertical side wall portion 96 is positioned closer to second side section 76 than is sloping side wall portion 86.

Means for holding that portion of the stationary magnet, which is adjacent first side section 72, within window 74 is provided by a resilient spring clip 100 shown in FIG. 4. Similarly means for holding that portion of the stationary magnet, which is adjacent second side 76, within window 78 is provided by a second spring clip 102. Since second spring clip 102 is identical in configuration, operation and installation to first spring clip 100, only details relating to the structure of spring clip 102, its installation and operation will be explained. As shown in FIG. 3, spring clip 102, which is made of a suitably structured metal or plastic, is comprised of first and second base sections 104 and 106, respective curled end sections 108 and 110, and a medial looped section 112 extending between base sections 104 and 106. Curled end sections 108 and 110 provide spring clip 102 with the required degree of resiliency necessary for its successful operation, and they are suitably located within appropriate slots formed in the interior of respective lower molded half sections 14a and 14b of the housing (not shown). As shown in FIGS. 3 and 4, those portions of base sections 104 and 106 adjacent looped section 112 of spring clip 102 are positioned within second channel 86 and abut bottom portion 94 and vertical side wall portion 96 so that stationary magnet 54 is firmly held within window 78 and cannot move toward first side section 72. Loopend section 112 extends past the upper most edge of vertical side wall section 96 and over the top surface of stationary magnet 54. The analogous components of spring clip 100 are also positioned within channel 84 to hold stationary magnet 54 firmly within window 74 so that the stationary magnet cannot move toward second side section 76.

In operation, a suitable tool such as a screwdriver 114 has its end positioned between looped section 112 of spring clip 102 and the top surface of stationary magnet 54. The tool is then moved downward as indicated in FIGS. 1 and 4 by an operator until those portions of base sections 104 and 106 of spring clip 102 are forced upward and out of engagement with vertical side wall portion 96 bounding second channel 86. Now the operator places his fingers within window 78 and pushes against the side of stationary magnet 54 so as to move stationary magnet 54 out from window 78, through opening 26 in coil 24 and out of the housing through window 74. Those sections of spring clip 100, which are initially positioned within bottom portion 88 and adjacent vertical side wall portion 90 bounding channel 84, glide up over sloping side wall portion 92 and onto the top surface of stationary magnet 54. Stationary magnet 54 continues its movement out of the housing through window 74 until it is no longer positioned within opening 26 of coil 24. Finally the above mentioned sections of spring clip 100 slide down sloping side wall section 98 and into second channel 86 in such a manner as to abut vertical side wall portion 96, and thereby prevent the complete removal of the stationary magnet from the housing. Now, by applying sufficient pressure to coil 24 to overcome the holding force of flat spring member 64, coil 24 is easily removed from the housing through window 58 in front section 56. Coil 24 is then either repaired, remodeled or replaced with another suitable coil. The new or re-

paired coil is then repositioned within the housing through window 58 in front section 56 until it again is in its proper assembled position. Then stationary magnet 54 is pushed back to its assembled position within the housing from window 74, through opening 26 in 5 coil 24 and into window 78 until spring clip 100 engages substantially vertical side wall portion 90 bounding channel 84 and spring clip 102 engages substantially vertical side wall portion 96 bounding channel 86. Alternatively, the screwdriver can be used to force 10 spring clip 100 out of engagement with vertical side wall portion 90 so that the stationary magnet can be pushed out of the housing through window 76 to enable removal of coil 24 from the housing.

It is thus seen that the just described configuration 15 provides for easy and fast removal and a replacement of the operating coil without requiring the undesired disassembly of the relay housing and most of its components.

It should be noted that in another form of the invention rear window 62 in rear section 60 of the housing can be eliminated, and the adjacent end of coil 24 can 20 rest on an inwardly extending molded ledge which can be formed in the interior of rear section 60. Similarly, both window 78 in second side section 76 of the housing and spring clip 102 can be eliminated, and the adjacent end 25 87 of stationary magnet 54 can rest upon an inwardly extending ledge which can be formed in the interior of second side section 76. Under these circumstances, once the means for holding a stationary magnet within window 74 in first side section 72 of the housing is released, stationary magnet 54 would have to be pulled rather than pushed through window 74 until it is clear of opening 26 in coil 24. Under these circumstances it may be necessary to provide means, such as a hook, attached to end 85 of the stationary magnet to facilitate the pulling of stationary magnet 54 through window 74.

Although the invention has been described with reference to a specific embodiment thereof, numerous modifications are possible without departing from the invention and it is desirable to cover all modifications of the invention falling within the spirit and scope of this invention.

What I claim as new and desire to secure by Letters Patent of the United States is:

1. An electromagnetic switching device comprising:

- a. a housing having front and rear sections and first and second side sections interposed between said front and rear sections, said front section and said first side section having windows extending therethrough;
- b. a movable magnet mounted in said housing for reciprocal movement between an energized and a de-energized position;
- c. an operating coil for energizing said device positioned in said housing, said coil having an opening therethrough, one end of said coil being retained within the window in the front section of said housing;
- d. a stationary magnet positioned within the opening in said coil and in juxtaposition with said movable magnet;
- e. switch means;
- f. means for actuating said switch means in response to movement of said movable magnet; and

g. a first spring clip having a first and a second part positioned within said housing, said first part of said first spring clip being in locking engagement with said stationary magnet for holding that portion of said stationary magnet adjacent one end thereof within the window in said first side section of said housing to prevent removal of said coil through the window in said front section, said second part of said first spring clip extending from said first part and over the top surface of said stationary magnet, whereby a tool is receivable between the top surface of said stationary magnet and said second part of said first spring clip, and upon proper movement of the tool, said first part of said first spring clip is moved out of locking engagement with said stationary magnet, thereby rendering said stationary magnet removable from the opening in said coil to enable said coil to be removed from said housing through the window in said front section.

2. An electromagnetic switching device according to claim 1, wherein said rear section and said second side section have windows extending therethrough, and the windows in said front and rear sections and said first and second side sections are each partially bounded by a bottom ledge.

3. An electromagnetic switching device according to claim 2, wherein said coil has a top surface and a bottom surface, further comprising a bowed spring positioned within said housing and bearing against the top surface of said coil to press those portions of the bottom surface of said coil adjacent said one end and another end thereof against the bottom ledge bounding the windows in said respective front and rear sections.

4. An electromagnetic switching device according to claim 2, further comprising a second spring clip having a first and a second part positioned within said housing both before and after said coil is removed from said housing, said first part of said second spring clip being in locking engagement with said stationary magnet for holding that portion of said stationary magnet adjacent another end thereof within the window in said second side section, said second part of said second spring clip extending from said first part of said second spring clip and over the top surface of said stationary magnet, whereby a tool is receivable between the top surface of said stationary magnet and said second part of said second spring clip, and upon proper movement of the tool, said first part of said second spring clip is moved out of locking engagement with said stationary magnet, thereby rendering said stationary magnet removable from the window in said second side section, through the opening in said coil, and then out of said housing through the window in said first side section.

5. An electromagnetic switching device according to claim 4, wherein said stationary magnet has a first and a second channel formed within a top surface thereof, said first channel being adjacent said one end of said stationary magnet, and said second channel being adjacent said other end of said stationary magnet.

6. An electromagnetic switching device according to claim 5, wherein each of said first and second channels is bounded by a bottom portion, a substantially vertical side wall portion extending from one edge of said bottom portion, and a sloping side wall portion extending from an opposite edge of said bottom portion and away from said vertical side wall portion.

7. An electromagnetic switching device according to claim 6, wherein said one end of said stationary magnet is closer to said substantially vertical side wall portion bounding said first channel than to said sloping side wall portion bounding said first channel, and said other end of said stationary magnet is closer to said substantially vertical side wall portion bounding said second channel than to said sloping side wall portion bounding said second channel.

8. An electromagnetic switching device according to claim 7, wherein said first part of said second spring clip engages said bottom portion and said substantially vertical side wall portion bounding said second channel to prevent said stationary magnet from moving in a direction toward the window in said first side section of said housing, whereby upon proper movement of the tool, said first part of said second clip is lifted over and out of engagement with said substantially vertical side wall portion bounding said second channel, thereby re-

leasing said stationary magnet for movement in the direction toward the window in said first side section of said housing.

9. An electromagnetic switching device according to claim 8, wherein said first part of said first spring clip engages said bottom portion and said substantially vertical side wall portion bounding said first channel to prevent said stationary magnet from moving in a direction toward the window in said second side section of said housing, whereby after said stationary magnet has been released and moved in a direction toward the window in said first side section of said housing, said first spring clip engages said bottom portion and said substantially vertical side wall portion bounding said second channel to prevent the removal of said stationary magnet from said housing while said coil is being removed from said housing.
